GOVERNOR MECHANISM

Joseph S. Dale, Rockford, Ill.

Application March 18, 1946, Serial No. 655,086

4 Claims. (Cl. 264—14)

1

This invention relates to governor mechanism and is particularly applicable to governors of the hydraulic type.

An object of the invention is to provide a governor of simple construction, capable of responding more quickly to speed changes and correcting such changes more rapidly than governors heretofore employed. A further object is to provide a governor structure in which improved control means are provided, regulating more accurately the flow of pressure fluid to the servomotor. Yet another object is to provide a novel fluid control valve mechanism in which the force resulting from dynamic unbalance is reduced to a minimum and is not transmitted to the speeder spring and fly weights. Another object is to provide a governor structure in which novel speed adjustment mechanisms and speed droop adjustment devices are provided. Yet another object is to provide a spring drive mechanism whereby effective rotation of the fly weights is accomplished, while at the same time absorbing slight oscillations of the prime mover. Other specific objects and advantages will appear as the specification proceeds.

The invention is illustrated, in preferred embodiments, by the accompanying drawings, in which—

Figure 1 is a perspective view of governor mechanism embodying my invention; Figs. 2 and 2', vertical sectional views, the section being taken as indicated at line 2—2 of Fig. 1 but showing two different constructions; Figs. 3, 3' and 3'', transverse sectional views, the sections being taken as indicated at line 3—3 of Fig. 2' but showing three different constructions; Fig. 4, a transverse sectional view, the section being taken as indicated at line 4—4 of Fig. 2'; Fig. 5, a broken view similar to Fig. 2' but showing a modified form of the invention; Fig. 6, a perspective view of the main drive shaft or ball head drive shaft employed; Fig. 7, a perspective view of a modified form of the valve sleeve employed; Fig. 8, a broken sectional view of a drive shaft equipped with a spring drive member; and Fig. 9, a transverse sectional view, the section being taken as indicated at line 9—9 of Fig. 8. Similar reference numerals are applied to corresponding parts throughout the views. For example, corresponding parts in Fig. 2 are given prime numerals to show relationship to corresponding parts in Fig. 2'.

In the illustration given, A designates the casing structure employed; B, control mechanism for supplying pressure fluid in response to speed

2

changes of the prime mover; and C, adjustment means for controlling the load on the speeder spring under various operating conditions.

The casing A may be of any suitable construction. In the particular illustration given, 5 10 designates a base plate, 11, a block or frame structure carried by the plate 10, and 12, a dome structure resting upon the body member 11. The dome member 12 is provided with a flange base 10 13 through which screws 14, Fig. 2', extend to secure the dome in place on the block 11, other screws 14', Fig. 2', being provided to fasten the base plate 10 to the block 11. A gasket 15 may 15 be provided between the flange structure 13 and the block 11. Another gasket 15 is provided between the base plate 10 and the block 11.

The block 11 may be formed of a solid piece of metal, or a cored casting, having openings therethrough providing a pump chamber, shaft openings, and conduits for the supply of fluids, etc.

The dome casing 12 is provided at its top with a shoulder 17. A recess 16 is provided under the cap 9' (Fig. 2), or the cap 9 (Fig. 2'). In the construction shown in Fig. 2, the cap 9' is held to the dome 12' by cap screws. In the construction shown in Fig. 2', the cap 9 is threaded engaged to the dome 12. The casing 12 provides in its interior a chamber adapted to receive the fly weight mechanism, etc.

30 The control mechanism B may be of any suitable type or structure. In the illustration given, I provide a ball head 18, equipped with a reduced extension 19. In Fig. 2, a collar 21' is pressed on extension 19 and bears against shoulder 17' to retain the ball head 18' in place. In Fig. 2', the extension 19 is tapped to receive a threaded bolt 20. The bolt 20 carries a flange 21 which rests upon the shoulder 17, thus holding the ball head 18 in place. The fly weights 22 are secured to the ball head 18 by the pivot pins 23 and are free to swing inwardly or outwardly about pins 23. Each of the fly weights 22 is provided with an integral arm 24 extending inwardly and equipped with a toe 25 turned downwardly. The ball head 18 is provided with an integral key 26 for securing the ball head 18 to the ball head drive shaft 27.

The main drive shaft 27, which may also be referred to as the ball head drive shaft, extends vertically through the casing members 10 and 11 into the dome 12, and is provided at its lower end with a slot 28 suitable for connecting it to the driven part of the prime mover. Shaft 27, therefore, rotates in synchronism with the driven part of the prime mover. Shaft 27 rotates in

bore 33 and is provided near its lower end with an integral gear member 29 which serves as a part of the gear pump which will be later described. Above the gear 29, the block 11 is provided with outlet ports 30 leading to the sump of the prime mover or any other desired collection point for the pressure fluid, through chamber 30^a and passage 30^b. Above the ports 30 on the shaft 27 are two spaced lands 31 and 32 which, when enclosed by a sleeve 40, as will be later described, provide between them a chamber 51 for the pressure fluid. Covered by the land 31 are a series of control ports 47 in the sleeve 40 which are effective in controlling the flow of fluid to and from the servomotor. Shaft 27 is provided with a slot 34 which receives the key 26 of the ball head 18 and thus establishes a connection for the rotation of the ball head 18 by means of the shaft 27.

Supported within the chamber of the dome 12 and between the fly weights 22 is an inverted frusto-conical speeder spring 35. The lower end of the spring rests upon a speeder spring seat 36. The upper part of the spring supports a cup member 37 which provides a shoulder 38 at its lower end. Resting upon the shoulder 38 is the flange 39 of the pilot valve sleeve 40. Above the sleeve 40 is a ball thrust bearing 41, the lower race of which rests upon the flange 39 and the upper race of which engages the toes 25 of the fly ball arms 24. The speeder spring seat 36 is preferably equipped with an integral, upwardly-extending sleeve 42 which serves to guide the seat 36. Preferably, the sleeve 42 extends also slightly below the seat 36. The spring seat 36 and sleeve 42 receive and are guided by a bushing 43 which is pressed into the bore 33 provided in block 11, this bushing 43 being one of three (43^a and 43^b) pressed into the bore 33 in spaced relation to one another to provide annular chambers 45 and 48 around the sleeve 40 in the vicinity of ports 44 and 47.

The pilot valve sleeve 40 is preferably formed of thin metal so that it will be light and may be moved easily longitudinally of the shaft 27 to provide an accurate control of the flow of the pressure fluid. It is suspended from the upper spring seat 37 by means of its flange 39 resting on the shoulder 38 and moves downwardly in response to pressure exerted upon the ball thrust bearing 41 by the toes 25 of the fly ball arms 24. The sleeve 40 is provided with inlet ports 44 and the control ports 47 previously mentioned. The inlet ports 44 register with the chamber 45 fed by the fluid conduit 46. The outlet, or control, ports 47 register with the annular chamber 48 which communicates with a conduit 49 leading to the servomotor chamber 50 (Fig. 4). The ports 47 cooperate with the land 31 of shaft 27 in controlling the flow of fluid from the annular chamber 51 provided between lands 31 and 32 and into the servomotor conduit 49.

For supplying fluid under pressure for the operation of the servomotor, I provide a gear pump which consists of gear 29 on shaft 27, and an idler gear 52 meshing with gear 29, as shown in Fig. 2'. The gears 29 and 52, as shown in Fig. 2', are mounted in recesses provided in the lower portion of casing block 11. Fluid is supplied to the pump by any suitable means. Three forms of relief valves are shown in Figs. 3, 3' and 3''.

In Fig. 3, the block 11, or 11' as the case may be, is provided with a reamed diameter hole 64 and a reamed diameter hole 57. A ball 62, spring loaded, as at 64, and held against seat 63, acts

as a relief valve. Lubricating oil is admitted to the governor from the prime mover lubricating pump through channel 56 in fitting 53. This fluid goes through channel 59 to the suction side of the gear pump formed by the gears 29 and 52. This fluid under pressure goes to channel 60. The spring 64 determines the maximum fluid pressure. If pressure is sufficient, the ball 62 is lifted off of the seat 63, allowing the fluid to flow past the ball 62 to the channel 29 as the suction side of the gear pump.

Fig. 3' illustrates a second method using a plunger 62^a instead of the ball 62.

Fig. 3'' illustrates a third method. In the illustration given, the block 11 is provided with a tapped opening receiving the fitting 53^a, as shown in Fig. 3''. The fitting 53^a is provided with a threaded opening 54 adapted to receive a pipe 55, as shown in Fig. 1, said pipe leading to any suitable source of supply, as, for example, the lubricant pump of the prime mover. Incoming fluid passes through the opening 56^a of the fitting 53^a and into the spring chamber 57^b provided in the fitting 53^a. A port 58 permits the liquid to flow into the inlet conduit 59, leading to the inlet side of the gear pump. The gear pump forces the liquid under pressure through conduit 60 into the passage 61, which is normally closed by the plunger 62^b. The plunger 62^b is urged toward stop pin 63^a by the spring 64. When the pressure of the fluid overcomes the pressure of spring 64, the plunger 62^b moves, compressing the spring, and uncovers port 65. Fluid is thus permitted to escape through relief port 65 and to return to the inlet side of the gear pump. By the means described, a predetermined pressure is maintained within the outlet passage of the pump, while at the same time a relief is furnished against excessive pressures. The conduit 46 leads off from the passage 61 to supply fluid to the chamber 51 about shaft 27.

It should be obvious that in the event of a reverse direction of drive for shaft 27, the gear pump, being driven in the opposite direction, makes the passage 60 the inlet and passage 59 the outlet, and in such event the plug 53^a will be entered in hole 53, plug 53^b being interchanged with plug 53^a.

The adjustment mechanism varying the elevation of the speeder spring seat 36 may be of any suitable construction. Three methods are illustrated in Figs. 2, 2' and Fig. 5.

In the illustration in Fig. 2, I provide an arm 89 which bears intermediate its ends under the spring seat 36', the plunger 83' through the ball 84', and the cam 91 which is fastened by screws to the cutaway section of the speed-adjusting shaft 72'. The speed-adjusting shaft 72' through the cam 91 raises or lowers the spring seat 36', thus changing the speed setting of the governor. With a fixed setting of shaft 72', as the load on the prime mover increases the servomotor moves outwardly, and the cam 78', due to the setting made by the screw 84', allows the plunger 83' to move downwardly. This lowers the ball 88' and the point of contact between arm 89 and the spring seat 36', thus giving a lower speed setting as the servomotor 19' moves outwardly. Thus, we have speed droop and a stable operating governor. This is the speed droop adjustment more fully described hereafter by reference to Figs. 2' and 4.

The construction shown in Fig. 5 is the same as illustrated in Fig. 2 except that the arm 89^a is pinned to the plunger 83^a by the pin 68'.

In the illustration in Fig. 2', I provide a fork member 66, having its forked end portion extending around the sleeve 42 and engaging the flange seat 36, as illustrated in Fig. 2'. The rear portion of the fork 66 is provided with a boss 67 which is secured by pin 69 to a block member 69. The block member 69 is also pivotally mounted upon pin 70 which secures it to the block 11. In order to raise or lower the fork 66 and thereby the spring seat 36, I provide a rotatable cam member 71 which has a cylindrical shaft portion 72 extending outside of the block 11, as illustrated in Fig. 1, and provided with a slot 73 by means of which the shaft 72 may be rotated. The inner cam portion 71 may be shaped as illustrated in Fig. 2', and the rotation thereof will elevate fork 66 and thereby the spring seat 36.

I provide special means herein for automatically taking care of speed droop. Speed droop, which is a decrease in governor speed setting as the servo is opened, is used for stabilization. Mounted within the servomotor chamber 58 of casing 11 is the servo plunger 74, as illustrated in Fig. 4. The plunger 74 is provided with a forked outer end 75 for connection to a control rod (not shown) connected to a fuel pump, gas mixing valve, steam throttle or other device for controlling the supply of fuel or other energy medium to the prime mover. The plunger 74 is provided on its lower side with a keyway 76 in which a key 77 extends, the key being pressed in a hole provided therefor in block 11, as illustrated in Fig. 4. A cam member 78 is mounted for pivotal movement upwardly and downwardly upon pin 79 carried on the inner end of plunger 74 and said cam 78, and is adapted to engage the flattened ball 80. The elevation of the cam member 78 is controlled by a threaded pin 81, having an inwardly-extending point engaging the cam and an outwardly-slotted portion 82 adapted to be engaged by a screw driver for inward or outward adjustment of pin 81.

The correcting influence of cam 78, in connection with speed droop, is transmitted through the flattened ball 80 and other mechanism in order to adjust the speeder spring seat 36. In this mechanism, a plunger 83 is provided with a rounded seat receiving the upper portion of ball 80 and with another rounded seat receiving the lower portion of upper ball 84. The upper ball 84 bears against block 69 at a point inwardly from the pivot pin 70, as illustrated in Fig. 2'. Above the block is mounted a leaf spring 34^a which maintains a constant downward pressure upon block 69, ball 84, and plunger 83, and thus through ball 80 exerts a downward force on cam 78. An upward thrust by the cam 78 during the movement of the servomotor will cause the ball members 80 and 84, through the plunger 83, to elevate the fork member 66 at a point inwardly from the pivot pin 70, and thus will tilt downwardly the inner end of fork 66 so as to lower the speeder spring seat 36. Likewise, cam 78 may permit a lowering of these members which will produce a corresponding rise of the speeder spring seat 36.

Shaft 27 is undercut between lands 32 and 108, thus forming a chamber 107. A cross-hole 106 is drilled in shaft 27, and a longitudinal hole 108 of larger diameter than the width of the key 26 is also drilled in shaft 27. Pressure oil will leak over land 32 into chamber 107. This oil will be forced through holes 106 and 108 into chamber 16, where it serves as a lubricant for the ball head, this oil eventually finding its way

to chamber 30^a communicating with the sump of the prime mover.

Operation

In the operation of the governor, as shown in Figs. 2 and 3, the pressure fluid enters the block 11, through the passage 56 in fitting 53, as shown in Fig. 3, through chamber 57' to the inlet conduit 59 to the gear pump, which will force the fluid through conduit 60 and upwardly into chamber 57^a and conduit 61. If the pressure here becomes excessive, the ball 62 is forced off the seat 63, against the spring 64, thus allowing the fluid to flow past the ball 62 into the chamber 57 to the inlet conduit 59 of the gear pump. By this means described, the fluid within the conduit 61 is maintained at the desired pressure and provides a supply of fluid under pressure to the conduit 46' leading to the chamber 51' provided between the shaft 27' and the pilot valve sleeve 40'.

In the operation of the governor, as shown in Figs. 2 and 3', the pressure fluid enters the block 11, through the passage 56 in fitting 53, as shown in Fig. 3, through chamber 57' to the inlet conduit 59 to the gear pump, which will force the fluid through conduit 60 and upwardly into chamber 57^a and conduit 61. If the pressure here becomes excessive, the plunger 62^a is forced off the seat 63, against the spring 64, thus allowing the fluid to flow past the plunger 62^a into the chamber 57 to the inlet conduit 59 of the gear pump. By this means described, the fluid within the conduit 61 is maintained at the desired pressure and provides a supply of fluid under pressure to the conduit 46' leading to the chamber 51' provided between the shaft 27' and the pilot valve sleeve 40'.

In the operation of the governor, as shown in Figs. 2' and 3', the pressure fluid enters the block 11 through passage 56^a and port 58, as shown in Fig. 3'', to the inlet conduit 59 of the gear pump, which will force the fluid through outlet conduit 60 and upwardly into conduit 61. If pressure here becomes excessive, plunger 62^b is moved sufficiently to uncover port 65, thus allowing the return of pressure fluid to the inlet side of the pump. By the means described, the fluid within conduit 61 is maintained at the desired pressure and provides a supply of fluid under pressure for conduit 46 leading to the chamber 51 provided between shaft 27 and pilot valve sleeve 40.

Shaft 27, which is connected to a driven part of the prime mover, rotates with said driven part and produces a similar rotation of the ball head 18, which is suspended upon bearing 17. Upon an increase in speed, the fly weights 22 tend to swing outwardly, and this action causes the arms 24, which are rigid with the fly weights 22, to move downwardly and to press their toes 25 against the upper race of the ball bearing 41. The downward movement of bearing 41 is resisted by speeder spring 35 and causes a corresponding downward movement of pilot valve sleeve 40.

As the pilot valve sleeve 40 moves downwardly under the thrust of the fly weights 22, the lower portions of the ports 47 are opened. The servo piston or plunger 74 is externally spring loaded (not shown) so that the spring tends to move the servo plunger inwardly to "fuel-off" position. The lower portion of the control ports 47 being opened, allows more oil to flow from the channel or conduit 49 into the space between the sleeve 40 and shaft 27, and thus to escape through the

dump ports 30. The escape of the pressure fluid gives a lower fluid pressure on the servo piston or plunger 74 and the piston is, therefore, free to yield to the action of the servo pull-back spring. The inward movement of the servo piston or plunger 74 toward the "fuel-off" position results in a slowing down of the prime mover.

The operation of the governor is exactly in the reverse direction when the speed of the prime mover, as reflected by the speed of rotation of shaft 27, is decreased. In this action, the reduction in centrifugal force causes the fly weights 22 to swing inwardly and the pressure upon the bearing 41 is reduced. Speeder spring 35, therefore, raises the shoulder 38 and thereby the pilot valve sleeve 40. Upward movement of the sleeve 40 closes the lower portion of the ports 47, thus cutting off the flow from channel 49 toward the dump ports 30, while causing the flow of pressure fluid from the chamber 51 into the servo conduit 49. The increase of pressure fluid in the servo chamber 50 causes the servo piston or plunger 74 to move outwardly and to overcome the pressure of the pull-back spring. This movement increases the fuel supplied to the prime mover and thus the speed of the prime mover increases.

As shown in Fig. 2, the speed setting of the governor is changed by rotating the shaft 12' so that the cam 91 raises or lowers the arm member 89. The arm member 89 in turn exerts pressure against the seat 36' to increase or decrease the loading of the speeder spring 35'.

As shown in Fig. 5, the speed setting of the governor is changed by rotating the shaft 72' so that the cam 91 raises or lowers the arm member 89a. The arm member 89a in turn exerts pressure against the seat 36' to increase or decrease the loading of the speeder spring 35'.

As shown in Fig. 2', the speed setting of the governor is changed by rotating the shaft 72 so that the cam 71 raises or lowers the fork member 66. The fork member 66 in turn exerts pressure against the seat 36 to increase the loading of speeder spring 35, or, upon lowering of the fork, to reduce the loading of the spring 35.

With respect to speed droop, if the speed of the prime mover and the governor decreases, then the servo piston or plunger 74 moves outwardly. As illustrated in Fig. 2, this movement causes the cam 78', when the cam is adjusted to the desired angular position by means of the pin 81', to move the ball members 80' and 84' and the plunger 83'. If the members are lowered, they lower the end of the arm 89, thus lowering the spring seat 36' and thus reducing the load on the speeder spring 35'. The opposite or inward movement of the servo piston or plunger 74' increases the loading on the speeder spring 35'.

With respect to speed droop, if the speed of the prime mover and the governor decreases, then the servo piston or plunger 74 moves outwardly. As illustrated in Fig. 5, this movement causes the cam 78', when the cam is adjusted to the desired angular position by means of the pin 68', to move the ball members 80' and 84' and the plunger 83'. If the members are lowered, they lower the end of the arm 89a, thus lowering the spring seat 36' and thus reducing the load on the speeder spring 35'. The opposite or inward movement of the servo piston or plunger 74' increases the loading on the speeder spring 35'.

With respect to speed droop, if the speed of the prime mover and the governor decreases, then the servo piston or plunger 74 moves outwardly. As illustrated in Fig. 2', this movement causes cam 78, when the cam is adjusted to the desired

angular position by means of pin 81, to move the ball members 80 and 84 and plunger 83. If the ball members are raised, they move the outer portion 67 of the fork 66 upwardly so that the inner end of the fork drops downwardly. This allows seat 36 to drop and decreases the loading of the spring 35. The opposite movement allows the spring 34 to move the outer portion 67 of fork 66 in a downward direction and thus raises the forked end of member 66 and seat 36, whereby the loading of spring 35 is increased.

The effect of the new structure upon dynamic unbalance should be mentioned. When oil flows over a land and through a port, a force is set up which tends to close the port opening in prior pilot valve structures. This force in prior structure is exerted on the land and is transmitted to the speeder spring and fly balls or weights. In my new structure as above described, the land 31 or 31', as the case may be, is on the shaft 27 which is held in a fixed vertical position, and this force is therefore not transmitted to the speeder spring 35 and fly balls 22.

The reduction in thickness of the sleeve 40 minimizes the reaction force transmitted to the fly balls 22 and speeder spring 35.

Any suitable means for closing the servo chamber 50 may be employed. In the illustration given in Fig. 4, the opening of the servo chamber is closed by a cover 86 secured by four screws 87, or other means, to the block 11.

It will be understood that the pilot valve sleeve heretofore described may be modified widely. In the illustration given in Fig. 7, a sleeve 40a is employed, having a flange 39a near the top portion thereof adapted to rest upon the shoulder 38 of the upper spring seat 37. With this structure, the tube is equipped with an extension 94 receiving the shaft 27 and lying within the ball bearing 41.

One difficulty with governors now in use is that with certain prime movers, oscillations of the prime mover will be transmitted to the governor, causing an uneven operation of the governor that is objectionable. To overcome this difficulty, I have provided a flexible or resilient spring drive which will transmit force from the prime mover to rotate the ball head but will not transmit the slight oscillations referred to. Such movements are absorbed in the spring connection and, therefore, do not adversely affect the operation of the governor.

In the structure shown in Figs. 8 and 9, I provide a shaft 95 which is substantially identical with shaft 27 except that it is provided with a longitudinal channel 96. I employ a spring wire 97 to connect the lower portion of the shaft 95 and an upper driving head 98. A hole 99 is drilled into the lower portion of the shaft 95, and the spring wire 97 is made fast within this hole, either by a pressed fit, threaded engagement, welding, or other means. Similarly, the upper end of the spring wire 97 is fixed to the shank 100 of the coupler head 98. The head 98 is provided with a narrow slot 101 which is substantially the same as the slot 34 of shaft 27. The slot 101 opens, however, into a flared slot 102 formed in the upper end portion 103 of the shaft 95, as shown more clearly in Fig. 9. The key 26' on the ball head 70 has one portion 104 fitting closely in slot 101 and has two depending end portions 105 which have a lost motion fit in the flared slots 102. With this construction, the head 98 will always drive the ball head 18' through spring 97 as long as the spring is effective. Should the spring 97

break and no longer be sufficient to carry the load from shaft 95 to head 98, the key 26' of the ball head 18' will engage its lower portions 105 in the flared slot 102 in the upper end 103 of shaft 95 and thus shaft 95 will directly drive by means of slot 102 the key 26' of ball head 18'.

With the modified structure shown in Figs.8 and 9, it will be seen that I have provided a structure which will normally drive the ball head 18' only through the resilient spring 97. By this means, any slight irregularities or oscillations of the prime mover will not be transmitted to the ball head but will be absorbed by the resilient member 97 itself. Should, however, the member 97 break or fail to carry the load, a direct drive is provided by means of the flared slot 102 in the upper end of the shaft 95, which slot will engage the key 26' the moment spring 97 becomes ineffective as a driving connection.

While in the foregoing description I have set forth a great variety of details as illustrating preferred embodiments of my invention, it will be understood that such details may be varied widely by those skilled in the art without departing from the spirit of my invention.

I claim:

1. In a speed governor adapted for use with a hydraulic servomotor to control the speed of a prime mover, control apparatus comprising a shaft adapted to be rotated by the prime mover and having thereon a pair of spaced lands, said shaft being held against axial movement, fly weights mounted on said shaft for rotation thereby, a speeder spring, a slideable valve tube mounted coaxially with the shaft and supported by the speeder spring, said tube being secured against rotation and operative to provide a chamber between said lands, inlet and outlet ports in said valve tube, and means carried by the fly weights for moving said valve tube against the force of said spring operative to vary the relative position of one of the lands and the outlet port and thereby to control the flow of fluid between the chamber and the servomotor.

2. In a speed governor adapted for use with a hydraulic servomotor to control the speed of a prime mover, control apparatus comprising a shaft adapted to be rotated by the prime mover and having thereon a pair of spaced lands, said shaft being held against axial movement, fly weights rotated by said shaft, a speeder spring supported to oppose movement of the fly weights, an axially-slideable valve tube mounted coaxially with the shaft and providing a fluid chamber between the lands, said tube being suspended from said spring and being provided with inlet and outlet ports, the outlet port being adapted to communicate with the servomotor and to regulate the supply of fluid thereto responsively to relative movement of the valve tube and the shaft.

3. In a speed governor adapted for use with a hydraulic servomotor to control the speed of a prime mover, control apparatus comprising a shaft adapted to be rotated by the prime mover and having thereon a pair of spaced lands, said shaft being held against axial movement, fly weights rotated by said shaft, a speeder spring supported to oppose movement of the fly weights, a thin, light valve sleeve mounted coaxially with said shaft and axially slideable thereon, said sleeve forming a fluid chamber between the lands and being supported by the speeder spring, means carried by the fly weights for moving said sleeve against the force of said speeder spring, and inlet and outlet ports in said valve sleeve, the outlet port being adapted to communicate with the servomotor and to regulate the supply of fluid thereto responsively to relative movement of the valve sleeve and the shaft.
4. In a speed governor adapted for use with a hydraulic servomotor to control the speed of a prime mover, control apparatus comprising a shaft adapted to be rotated by the prime mover and having thereon a pair of spaced lands, said shaft being held against axial movement, fly weights mounted for rotation by said shaft, a speeder spring, a valve sleeve in engagement with the speeder spring and mounted coaxially with the shaft and slideable thereon, said sleeve being operative to provide a chamber between said lands, an outlet port in said valve sleeve, and means for moving said valve sleeve axially against the force of said speeder spring responsively to movement of said fly weights, said axial movement of the sleeve being operative to vary the relative position of the outlet port and one of the lands.

JOSEPH S. DALE.
